UNITED STATES PATENT OFFICE.

WILLIAM E. ASPLIN AND HUGO A. WISANDER, OF WEST PARK, OHIO.

METHOD OF MAKING BASKETS.

Original application filed December 26, 1919, Serial No. 347,507. Divided and this application filed June 27, 1921. Serial No. 480,916.

To all whom it may concern:

Be it known that we, WILLIAM E. ASPLIN and HUGO A. WISANDER, citizens of the United States, residing at West Park, in the 5 county of Cuyahoga and State of Ohio, have invented certain new and useful Improvements in Methods of Making Baskets, of which the following is a specification.

Our invention relates to an improved 10 method of making baskets and similar receptacles, our invention embodying an improved basket forming mat together with improved means of preparing and folding the mat in the basket forming operation, as 15 disclosed but not claimed in our application filed December 26, 1919, Serial No. 347,507, for an apparatus for making baskets, and of which application this application is a divisional part.

20 The primary object of the invention is the provision of an improved method of making baskets which will not only simplify and improve the present methods, and which may be readily carried out thru a suitable machine or apparatus, but one which will improve upon the finished product.

With the above mentioned and other ends in view, the invention comprises the method hereinafter described, illustrated in one of 30 its embodiments in the accompanying drawings in connection with suitable apparatus for carrying the same into effect, and particularly pointed out in the appended claims.

Referring to the drawings, forming a part 35 of this specification, Figure 1 is a plan view of a basket forming mat of the veneer board type constructed in accordance with the initial steps of the improved method and preparatory to further forming, tacking and 40 completing in the improved machine for carrying out the improved method.

Fig. 2, a perspective view of a suitable machine, the conventional stapling or tacking device being somewhat diagrammatically illustrated, the improved mat being in 45 its initial folded position upon the improved rotatably mounted basket form and illustrating in particular the initial engagement of the initially folded sides of the basket 50 mat by the mat engaging members of the form preparatory to turning the basket form and mat for initially folding over the projecting binding strips and fastening one of

the intermediate lateral basket walls or sections.

Fig. 3, a view of the inner side of a partially completed basket, illustrating in particular the manner of folding over and tacking the intermediate basket walls and ends of the rim forming binding and tacking 60 strips.

Fig. 4, an enlarged rear view of the basket form or block and its oppositely arranged basket mat engaging members and actuating mechanism therefor, the parts being shown 65 in their closed or clamping positions after the initial mounting of the basket mat on the rotatable form and the movement of the latter for the folding over and fastening of the first intermediate basket wall or section 70 and the overlapping ends of the rim forming binding strips.

Fig. 5, a view of the rotatable basket form in its initial or horizontal basket mat receiving position, the mat clamping members or 75 jaws being open preparatory to receiving and having folded thereover two of its sides, the two walls of the basket mat carrying the binding strips and the clamping of the latter by such clamping jaws upon the further 80 movement of cycle of rotation of the form block for the further folding and fastening of the remaining basket wall or section.

Fig. 6, a side elevation of the machine, the rotatable basket form being shown in central 85 cross section taken on line 6—6 of Fig. 5, showing the rotatable form in horizontal or basket mat receiving position, the mat clamping members being open for such purpose.

Fig. 7, a longitudinal sectional view of the basket form taken on line 7—7 of Fig. 5.

Fig. 8, a perspective view of a means for resiliently connecting the connecting links between the mat clamping members and 95 the form actuated mechanism therefor, whereby a limited independent resilient or spring actuated movement of the ends of the mat clamping members will be permitted when closed or being closed by the movement of the block.

Similar numerals of reference designate like parts throughout all the figures of the drawings.

While we have shown our improved 105 method and apparatus in connection with a

basket of the oblong veneer type, it should be understood and will be obvious that the improved method may be carried out in connection with the manufacture of baskets 5 and similar receptacles of varying forms and sizes, and it will also be understood that the improvements may be readily incorporated in or used in connection with various basket making machines and appliances.

10 For the purpose of illustration we have shown our improvements applied to a basket stapling machine of the ordinary or conventional form or type.

In carrying out our improved method, we 15 provide a basket forming mat substantially as illustrated in Fig. 1 of the drawings. The mats may be made up of any suitable and convenient material and the material may be woven and secured in any suitable 20 and convenient manner.

As a means of forming the bottom and side walls or sections of the basket or receptacle, the strips of material are formed or laid so that the intersecting portions will 25 form the bottom section 1, and with projecting members or sections forming the lateral walls or sections of the basket when formed up as hereinafter referred to.

In the present instance, the projecting sections 30 1^a and 1^b, are adapted to form the basket side and end sections 1^a and 1^b, when folded and connected as hereinafter referred to.

In forming a basket of the veneer type, 35 the strips of veneer after being assembled, as stated, may be secured by means of staples 1^c. As contradistinguished from the present methods of preparing the basket mat, the marginal edges of two of the lateral 40 wall forming sections, (in the present instance, the basket side forming sections 1^a), are each provided with a pair of basket rim forming binding strips 2, which, in the present instance, are secured by means of staples 45 2^a, said strips having projecting portions 2^b, corresponding approximately in length to the width of the remaining or intermediate sections 1^b, (in the present instance, the end forming sections 1^b), said projecting portions 2^b, being adapted to engage and cover the marginal ends of the intermediate or end walls 1^b, as illustrated in Fig. 3 of the drawings.

After the mat has been prepared, as 55 stated, the next step in the method is to fold the sections 1^a, carrying the strips 2, inwardly, and as a means of conveniently effecting this step in the method a rotatably mounted basket form or block 3, is provided, said block 3, having exposed end and lateral surfaces and being adapted to receive and clamp the binding strips 2, and side sections 1^a, after the bottom and side sections of the mat are folded thereover, 60 as hereinafter more fully described, after

which the remaining or intermediate sections 1^b, (in the present instance the end sections), are folded over the ends of the block (after the initial inward folding of the inner projecting binding strips 2) and 70 the outer projecting binding strips are folded inwardly thereover and said overlapping parts are suitably secured by means of a suitable fastening device, in the present instance, a stapling device arranged in 75 suitable proximity to the ends of the rotatable block 3. In the present instance, the device is arranged to initially form, fold and bind the end walls 1^b, and projecting portions 2^b, of the strip in sequential order, 80 after which the clamping devices of the block are released and the completed basket body may be removed.

As a convenient means of carrying out our improved method in connection with the 85 improved apparatus, we have shown the latter in connection with a stapling machine of conventional form and such stapling machine as to its details forming no part of our invention need not be described in detail.

It will be seen that the fastening or stapling device, in the present instance, comprises a suitable supporting pedestal 4, having an arm 4^a, terminating in a stapling head 4^b, and a reciprocatory shaft 4^c, provided with a second arm 4^d, and having suitable attachments (not shown) adapted to control the stapling mechanism when brought into action by the foot lever 5, and the clutch 6, and driving shaft 7.

As a convenient means of mounting the basket form 3, beneath the stapling head 4^b, the block 3, is provided with a metallic head or base 3^a, the marginal edges of the latter 105 being adapted to support the basket rim or binding strips 2, and form an anvil for the insertion of the fastening devices or staples when driven through the portions 2^b, of the binding strips 2.

As a means of mounting the basket form 110 conjointly formed by the block 3, and base 3^a, in proper co-operative relation to the overhanging stapling head 4^b, a bearing arm 8, provided with a split head 8^a, is mounted on a supporting pedestal 4, said arm 8, terminating at its end in a reduced bearing spindle 8^b, adapted to support the bearing portion of the member 3, and to removably secure the latter by means of a retaining plate 8^c, and screw 8^d, as shown most clearly in Fig. 6 of the drawings.

As a means of removably clamping or securing the sides of the basket carrying the binding strips 2, so that the latter will be 125 securely retained in place while the opposite walls or end sections of the basket are being secured to the projecting portions 2^b, of the strips, the opposite sides or lateral surfaces of the block are provided with bas- 130

ket mat engaging members 9, said engaging members 9, being in the specific form of outwardly extending tongues or jaws 9, adapted to be moved toward and 5 away from the edges of the form or base portion 3^a, and forming the free ends of the lever members 9^a, the latter being pivotally secured at the rear of the metallic base portion 3^a, of the block by means of pivots 9^b, 10 in the present instance, in the form of bearing pins, said jaws or lever members being adapted to be simultaneously actuated and controlled by means of link members 10, connected to a spring resisted carrier member 15 or block 11. The links 10, may be secured to the movable block 11, by means of a cross member 12, removably secured by means of a bearing bolt 13, the latter also forming a bearing for a friction 20 roller 14, adapted to travel upon and be actuated by a cam 15, secured upon the end of the bearing arm 8.

The position of the flat portion of the cam 15, is such relative to the roller 14, of 25 the carrier block 11, and the jaws 9, on the lever members, 9^a, that when the basket form 3, is in a predetermined position (as for example, in a horizontal position, as shown in Figs. 5 and 6, of the drawings), the basket 30 engaging members or jaws 9, will be in an open position and the opposite sides of the basket mat are folded thereover and when the block is turned to one side to bring the intermediate section of the basket into position to be operated upon by the stapling 35 device, the carrier block 11, will close said jaws over the strips 2, as indicated in Fig. 2 of the drawings and hold the same in such position during the remaining cycle of rotation of the block and until it reaches its 40 original position, whereupon the jaws will be automatically opened for the removal of the completed basket from the forming block.

45 The carrier block 11, is adapted to operate in a guide way formed between undercut flanges 3^b, of the base 3^a, of the head or block 3, and the roller 14 of the carrier 11, may be held in engagement with the cam 15, 50 by means of a spring 16, arranged between a flanged member 3^c, of the base 3^a, and a lug 11^a, on the carrier block 11.

Should it be desired to permit some individual outward movement of the jaw and 55 lever members 9 and 9^a, to meet irregularities in the thickness of the binding strips 2, at the points of contact, the link members 10, may be formed in two parts as at 10^a and 10^b, in Fig. 8, of the drawings, said overlapping members terminating in lugs 10^c and 10^d, the lug 10^d, extending through a guide slot 10^e, and being provided with a guide bolt 17, surrounded by a compression spring 18, extending between the lugs 10^c and 10^d, 60 and as a means of adjusting the tension of

the spring 18, the guide bolt 17, may be provided with a flange or collar 18^a, and carried by the bolt 17, as the latter is adjusted through its head and operating in a well known and understood manner.

70 From the foregoing description, taken in connection with the accompanying drawings, the operation and advantages of our invention will be readily understood.

Having thus described the improved 75 method of making baskets, together with one of the forms or embodiments of a suitable apparatus or device for carrying the same into effect, what we claim and desire to secure by Letters Patent, is,—

80 1. A method of making baskets, comprising (1) providing a mat with a basket bottom forming section and basket side and end forming sections, (2) applying binding strips to said basket side forming sections 85 with ends thereof projecting to correspond with and cover the end forming sections when folded up, (3) folding said side sections and securing said binding strips thereon in substantially parallel relation, (4) 90 folding said end forming sections and the projecting ends of the binding strips inwardly over and securing the same to each other.

95 2. A method of making baskets, consisting in (1) forming a mat with members adapted to fold up and form the lateral walls of the basket body, (2) applying binding strips to opposite members with the ends thereof projecting to correspond approximately with 100 the width of the remaining or intermediate members of said mat, (3) folding said strip carrying members inwardly in substantially parallel relation, and (4) folding said intermediate walls and the ends of said binding 105 strips over the ends of said intermediate walls in overlapping relation, and (5) securing the latter and said overlapping end strips.

110 3. A method of making baskets, comprising (1) providing a mat with a central basket bottom forming section and projecting basket side and end forming sections, (2) applying basket rim forming binding strips to said basket side forming sections 115 with the ends thereof projecting sufficiently to engage and cover the marginal ends of said end forming sections when formed up, (3) folding said side sections inwardly over a form and securing said binding strips 120 thereon in substantially parallel relation, (4) folding said end forming sections and said projecting binding strips inwardly in overlapping relation and securing the same.

125 4. A method of making baskets, consisting in (1) forming a mat with projecting side and end members adapted to form the side and end walls of the basket body, (2) applying a binding strip to the marginal ends of said projecting side members with 130

4

the end thereof projecting to correspond approximately with the width of said end members and to fold over and engage the latter when the basket is formed, (3) simultaneously folding said side members inwardly over and clamping the same on a basket form, and (4) folding said projecting end walls and the projecting portions of said binding strip inwardly over the ends of 10 said basket form in overlapping relation and securing the same.

5. The method of making baskets, consisting in providing a mat with a bottom forming section and lateral sections adapted 15 to form the lateral walls of the basket when set up, (2) applying a pair of basket rim binding and tacking members to the opposite sides of the free edges of two of said lateral wall forming sections with projecting 20 ends adapted to overlap each other on the intermediate wall forming sections when folded up, (3) folding such strip carrying sections in parallel relation, (4) folding the inner binding strips on the inner sides of the in-

termediate wall forming sections, and (5) 25 folding the remaining outer binding strips over such sections and connecting the same.

6. The method of making baskets, consisting in providing a mat with a bottom forming section and oppositely arranged 30 sections adapted to form the lateral walls of the basket when set up, (2) applying basket rim forming binding members to the marginal edges of two of said lateral wall forming sections with projecting ends adapted to 35 overlap the intermediate wall forming sections when set up, (3) folding such strip carrying sections with said strips extending in parallel relation, (4) folding some of said binding strips upwardly to receive the intermediate sections, (5) folding such sections thereover and (6) folding the remaining binding strips over such sections and connecting the same.

In testimony whereof we have affixed our 45 signatures.

WILLIAM E. ASPLIN.
HUGO A. WISANDER.
